Peter N. Nelson, Chicago, Ill., assignor to Micro-Master Company, Chicago, Ill., a corporation of Illinois

Application January 6, 1943, Serial No. 109,208

Term of patent 14 years

To all whom it may concern:

Be it known that I, Peter N. Nelson, a citizen of the United States, residing at Chicago, in the county of Cook and State of Illinois, have invented a new, original, and ornamental Design for Indicating Calipers, of which the following is a specification, reference being had to the accompanying drawing, forming a part thereof.

Figure 1 is a front elevational view of the indicating calipers showing my new design;

Fig. 2 is a side elevational view thereof;

Fig. 3 is a top plan view.

I claim:

The ornamental design for indicating calipers, substantially as shown.

PETER N. NELSON.
